UNITED STATES PATENT OFFICE.

WILLIAM RAPHAËL BOISVERT, OF LEVIS, CANADA.

SPRING-BED.

SPECIFICATION forming part of Letters Patent No. 569,994, dated October 27, 1896.

Application filed May 13, 1896. Serial No. 591,364. (No model.)

To all whom it may concern:

Be it known that I, WILLIAM RAPHAËL BOISVERT, a citizen of the Dominion of Canada, residing at Levis, in the county of Levis 5 and Province of Quebec, Canada, have invented certain new and useful Improvements in Spring-Beds; and I do hereby declare the following to be a full, clear, and exact description of the invention, such as will enable others skilled in the art to which it appertains to make and use the same.

This invention relates to spring-beds; and it consists in the novel construction and combination of the parts hereinafter fully described and claimed.

In the drawings, Figure 1 is a plan view of the bed. Fig. 2 is a side view of the same.

A are three or more longitudinal bars, of iron or other strong material, provided with 20 upwardly-curved ends a'.

B are cross-pieces secured to the bottom portions of the bars A and holding them at the required distance apart.

C are cross-pieces secured to the upper end 25 portions of the series of bars A.

D are longitudinal bars, of steel or other spring material, having their ends secured to the bars C.

E are cross-bars, of steel or other spring 30 material, having their ends secured to the outer bars D of the series of longitudinal

spring-bars. The bars D and E are interlaced with each other, as shown in Fig. 1, and are free to slide in frictional contact with them.

F are springs secured to the lower parts 35 of the longitudinal bars A for the purpose of supporting their curved ends, and G are springs also secured to the bars A for supporting the middle parts of the spring-bars D. 40

The bars A, B, and C form a spring by which the interlaced spring-bars are supported.

What I claim is—

In a spring-bed, the combination, with a 45 series of longitudinal bars A provided with upwardly-curved ends, cross-pieces B secured to the said bars, and cross-pieces C secured to their said curved ends; of a series of spring-bars D secured to the cross-pieces C, a series 50 of spring cross-bars E secured to the outer bars D and interlaced with and slideable upon the intermediate bars D, and springs interposed between the bars A and their curved ends, and between the bars A and D, substantially as set forth.

In testimony whereof I affix my signature in presence of two witnesses.

WILLIAM RAPHAËL BOISVERT.
